ABSTRACT

A U-shaped bar of so-called remanent magnetic material serves as a core for actuating one or more magnetic reed switches that are mounted between the legs of the U with their magnetic axes generally parallel with the bight of the U. Two coils are positioned around the bight of the U, one wound upon an axis parallel to the bight, and the other wound on an axis orthogonal to the bight. The switch, or switches are latched selectively and alternately in either their closed or open position, depending on which of the two coils is energized. The condition of the device may be sensed magnetically in a manner similar to the reading of magnetic memory devices.

FIG. 4

LATCHABLE MAGNETIC REED SWITCH

BRIEF DESCRIPTION

This invention relates to novel electromechanical switching devices of the general kind described in U.S. Pat. No. 3,002,066, Ketchledge, et al., in which magnetically actuatable reed switches are mounted on or adjacent to a core of a remanent magnetic material for alternate opening and closing responsively to changes in the magnetic condition of the core.

In the patented device a pair of coils are mounted at opposite respective ends of a straight, bar-like core of a remanent magnetic material, and the reed switches are juxtaposed with the core. When the coils are energized simultaneously in a magnetically aiding direction, the core is magnetized to act like a single permanent magnet, the opposite ends of the core being driven to opposite respective magnetic polarities, and the switches are drawn and held closed. When, however, the coils are energized in magnetic opposition to each other, the core is magnetically divided into two opposed magnets. The ends of the core are both of one polarity, and the poles of the other polarity are near the center of the core. The switches are then biased and held open.

Other, more or less similar arrangements have also been proposed, some using a permanent magnet in place of one of Ketchledge's coils.

The previous arrangements have been subject to certain disadvantages and difficulties, especially in respect of driving the switches from their closed to their open positions. In the Ketchledge arrangement, for example, one must either energize both coils simultaneously at closely matched energy values, or energize one of the coils to a critical value, else the desired magnetic splitting of the core in half will not be achieved properly.

The present invention avoids this problem, and provides a switching device of improved versatility, simplicity, reliability, and ease of control.

Briefly, a switching device according to the invention includes a core of a remanent magnetic material that in its basic form is U-shaped, although in actual practice preferably H-shaped, resembling two U-shaped cores in a common plane with their bight portions integrally joined together. Magnetic reed switches are mounted between the legs of the U, and a pair of mutually orthogonal coils are mounted upon the bight of the U.

When the coil that is wound on an axis parallel to the bight is energized, the core is magnetized as a simple horseshoe magnet with the flux gap extending between the legs, through the reed switches, and the switches are driven closed. When, however, the coil wound on an axis parallel to the legs of the U is energized, the core becomes magnetized as a simple bar magnet, the legs are of the same magnetic polarity, and a force of repulsion is produced between the opposed reeds of the switches to open the switches and hold them open.

In the ordinary case, the energizing currents applied to the coils to actuate the switches are simply pulses of sufficient value and duration to saturate the core. Their magnitude is not critical, except as to a minimum value, and, so far as the magnetic action is concerned, it is not possible to overdrive the coils. Nor is it ever desired to energize both coils simultaneously. One coil actuates the switches to one position and leaves them latched there, and the other coil actuates the switches to the opposite position, and leaves them latched there. The

arrangement is simple, convenient, and non-critical in operation.

Auxiliary reed switches may be mounted alongside the legs of the cores for operation in opposite mode from the switches that extend between the legs. Thus, an off-normal switch may be included, or operation as a double throw switch may be readily achieved.

Finally, the magnetic condition of the core may be readily sensed through either one of the coils, or by a separate "sense" winding by pulse interrogation methods similar to those used for reading magnetic memory devices, preferably one of the non-destructive methods.

DETAILED DESCRIPTION

Representative embodiments of the invention will now be described in detail in conjunction with the accompanying drawing, wherein:

FIGS. 1A and 1B are schematic plan views of a typical device according to the invention illustrating the theory of operation on which it is based;

FIG. 2 is a plan view of a switching device according to a first, representative embodiment of the invention;

FIG. 3 is a side elevational view of the device shown in FIG. 2; and

FIG. 4 is a plan view of a second, and presently preferred embodiment of the invention.

As shown in FIGS. 1A and 1B, the core 10 is alternately switched between a "horseshoe" condition, FIG. 1A, and a "bar" condition, FIG. 1B, by alternately energizing the two coils 12 and 14 that are mounted on the bight portion 16 of the core orthogonally to each other. Reed switches 18, normally regarded as the main switches, are mounted between the legs 20 and 21 of the core, and other reed switches 24, the auxiliary switches or back contacts, are mounted alongside of and parallel to the legs.

The core 10 is preferably made of remanent magnetic material such as the alloy known commercially as Remadur, or certain ferrite compositions, that is capable of remaining magnetically saturated once it is driven to saturation by energization of one of the coils 12 and 14. Several materials having the desired remanence characteristics are commercially available and well known.

As shown in FIGS. 2 and 3, a typical switching device according to the invention may comprise a pair of H-shaped core pieces 30 and 31, each of which consists of two sheets of Remadur alloy about 0.015 inch thick. The core pieces are in face to face opposition and spaced apart about 0.1 inch, or just far enough to accommodate the main reed switches 34 and 35 that are mounted between their leg portions 32 and 33, respectively. In most utilizations three switches 34 and 35 at each end of the H, six in all, are all that are desired, although as many as five at each end, a total of 10, have been operated reliably by a core about 2 inches long and 1 1/2 inches wide.

The two coils 12 and 14 are mounted upon the bight portion 37 of the core, and are connected to any desired control circuit for selective alternate energization.

The instantaneous magnetic condition of the core may be ascertained by applying an electrical pulse of relatively small amplitude to one of the coils 12 and 14, and sensing the resulting and ensuing electrical effects in that coil or the other one, or in a separate "sense"

winding 38 that may be wound on the core adjacent to the two energizing coils. In general, the core may be treated as a magnetic memory element, and its condition may be read just as any other magnetic memory element is read. This effect is especially advantageous in switching arrays that include numerous switching devices. In these cases, the so-called sense windings 38 of all the cores in the array may be connected in series with each other, and the condition of a particular core ascertained by the effect on the sense windings immediately following the application of an "interrogating" pulse to the core of interest.

An alternative embodiment of the invention is shown in FIG. 4. It includes so-called off-normal contacts constituted by an auxiliary pair of reed switches 40 and 41 mounted alongside the core pieces 44. In this case, to maximize the magnetic flux applied to the off-normal contacts 40 and 41, the core pieces differ from the core pieces 30 and 31 shown in FIGS. 2 and 3 in that they include integrally formed tabs 47 extending laterally outwardly at the bight end of each leg. The off-normal contacts 40 and 41 operate oppositely from the main contacts 34 and 35, being open when the main contacts are closed, and vice versa.

Switching devices of the invention do not require reed switches of special design for the off-normal contacts. Instead, all of the reed switches in the devices may be of the standard type known commercially as Form A, in which the contacts are normally open, and are closed only in response to magnetic flux passing through them.

What is claimed is:

1. A magnetically controllable switching device comprising a U-shaped core of a remanent magnetic material, a magnetically responsive reed switch mounted be-

5 tween the opposed legs of said core with its magnetic axis generally parallel to the bight of said core, and a pair of energizing coils mounted upon the bight of said core, one of said coils having its winding axis parallel to the length of the bight, and the other one of said coils having its winding axis orthogonal to the bight.

10 2. A switching device according to claim 1 including an auxiliary magnetically responsive reed switch mounted alongside of one of the legs of said core and generally parallel thereto for actuation in an electrically opposite mode from said first named switch, being open when said first named switch is closed and vice versa.

15 3. A switching device according to claim 1 including an auxiliary winding upon a selected portion of said core for sensing the magnetic response to said core to a current of small amplitude and short duration passed through one of said pair of coils.

20 4. A magnetically controllable switching device comprising an H-shaped core of a remanent magnetic material, a magnetically responsive reed switch mounted between a selected pair of opposed legs of said core with its magnetic axis generally parallel to the cross-bar of the H, and a pair of energizing coils mounted on the cross-bar portion of said core, one of said coils being oriented with its winding axis parallel to the leg portions of the core, and the other one of said coils having its winding axis orthogonally thereto.

25 5. A switching device according to claim 4 including an auxiliary reed switch juxtaposed with said core laterally outwardly thereof for operation in an electrically opposite mode from said first named switch, being open when said first named switch is closed and vice versa.
